UNITED STATES PATENT OFFICE

2,102,175

MOLDER

Laurence E. Blood, Newton, Mass., assignor to S. A. Woods Machine Company, Boston, Mass., a corporation of Massachusetts

Application November 28, 1934, Serial No. 755,185

15 Claims. (Cl. 144—245)

This invention relates to molding machines and the object is to provide various improvements in the construction of such machines. The particular occasion for these improvements has been 5 the construction of a machine for cutting small rods from blanks of rotary-cut softwood veneer.

In the accompanying drawings illustrating an exemplary embodiment of my invention:

Fig. 1 is a simplified plan view of the machine; 10 Fig. 2 is a simplified side elevation;

Fig. 3 is a side elevation of the mechanism for feeding the work from a supply and delivering it to other mechanisms of the machine;

Fig. 4 is a partial elevation of the hopper shown 15 in Fig. 3 as seen from the left in that figure;

Fig. 5 is a plan view of the mechanism shown in Fig. 3;

Fig. 6 is a partial horizontal section of the hopper showing a portion of the feed chain in plan; 20

Fig. 7 is a section across the bed of the machine in front of the hopper, with parts omitted;

Fig. 8 is a side elevation and longitudinal section respectively of the feed chain and one of the feed dogs;

Fig. 9 is a section on line 9—9 of Fig. 7; 25

Fig. 10 is a side elevation of the feeding mechanism of the molder proper;

Fig. 11 is an enlarged vertical section and Fig. 30 12 is essentially a plan thereof, with parts omitted in both instances;

Fig. 13 is a plan view of the hold-down and chip breaker which intervene between the mechanism of Figs. 10, 11 and 12 and the top cutter head;

Fig. 14 is a side elevation thereof; 35

Fig. 15 is a vertical section on line 15—15 of Fig. 13;

Figs. 16 and 17 are respectively front and rear elevations of the chip breaker and framework 40 supporting the same;

Fig. 18 is a plan on the line 18—18 of Fig. 14;

Fig. 19 is a plan of the hold-down utilized between the two cutter heads;

Figs. 20, 21 and 22 are side, front and rear elevations thereof respectively; 45

Fig. 23 is a section on line 23—23 of Fig. 20;

Fig. 24 is a section on line 24—24 of Fig. 19;

Fig. 25 is an end view of the hold-down shoe;

Fig. 26 is a side view thereof; 50

Fig. 27 is a plan of the feeding-out works;

Fig. 28 is a side elevation thereof with parts broken away;

Fig. 29 is an end elevation as seen from the left of Fig. 26;

Fig. 30 is a section on line 30—30 of Fig. 27; 55

Fig. 31 is a sectional detail of the bed or platen between the cutter heads;

Fig. 32 is a diagrammatic end view of a typical work blank;

Fig. 33 is a view of the blank after the operation thereon of the top head; and Fig. 34 is an end elevation showing the completed work as delivered from the machine. 5

All the drawings are considerably simplified and many parts have been omitted for clearness 10 since, in so far as necessary or desirable, they will readily be supplied by those skilled in the art and may be of forms in themselves well known. In particular Figs. 1 and 2 are primarily intended to serve as diagrams for correlating the 15 other figures which show the parts on a larger scale, it being impractical to disclose the entire machine in a single view on a satisfactory scale within the limits of a patent drawing.

The construction, purpose and function of the 20 elements of the rod cutting machine illustrated may perhaps be more readily understood from a brief preliminary consideration of the operation effected thereby. The design of machine shown is intended to operate on rectangular blanks of 25 rotary-cut softwood veneer, as, for example, of poplar, say about $\frac{1}{16}$ of an inch thick. These blanks are fragile and tend to be warped, as indicated in Fig. 32 by an end view of a not unrepresentative blank. To be practical economically 30 the operation of the machine must necessarily be very rapid and in practice a machine of the type shown has been run at the rate of 140 feet per minute. The rods or sticks are formed by the molding operation of upper and lower cutter 35 heads 40 and 42 respectively (Fig. 2). The upper head 40 shapes the upper surface of the piece of stock forming the contour of the rods or sticks at one side and grooving the blank between them past the center line in the manner shown in Fig. 33. The lower head 42 shapes the bottom portion of the rods or sticks and separates them one 40 from another in the manner shown in Fig. 34.

Referring to Figs. 1 and 2, I will first generally identify the mechanisms utilized. The blanks 45 cut to a suitable size may be received in a vertical stack in the hopper 44 and are separated from the stack for feeding into the machine by means of a chain 46 having feed dogs 48 which carry away the lowermost blank from the stack. The 50 blanks are delivered by the chain 46 to a pair of fluted transfer rolls 50 which serve to advance them down a confining passageway, the upper wall of which consists of a hold-down mechanism 52, to the molding mechanism proper. The 55

feed of this molding mechanism is herein shown as comprising a circulating bed 54 with which cooperate pressure rolls 58 and this feeding mechanism advances the blanks in a continuous series, 5 one pushing forward those preceding it, herein beneath a hold-down plate 60 and the chip breaker 62 to the top head 40, from which the blank, shaped thereby to the form shown in Fig. 33, advances beneath a hold-down 64 to the bottom head 42 and thence to the feeding-out mechanism 66, the match sticks being finally delivered from the machine by the chute 68.

Referring now more particularly to Figs. 3 and 4, I will first describe the preliminary feed 15 means comprising the hopper 44 and the chain 46. In the construction of these parts, as in other parts of the machine, the fact will be observed that because of the somewhat irregular 20 nature of the blanks provision is made for controlling them by their side edges. The hopper for confining the stack of blanks may consist essentially of a number of vertical angle irons 70, as best seen from Fig. 6, which cooperate with the corners of the various blanks in the stack. The 25 bottom of the hopper is essentially formed by two rails 72, best seen in Fig. 7, underlying the longitudinal side edges of the blank. The flanges of the forward angles 70 overlying these rails are cut away, as seen at 74 in Fig. 7, to define an exit 30 opening, preferably tapered outwardly to the desired size as shown, thus providing fences facing solely the side edges. The front of the hopper is substantially unobstructed between these lateral fences; that is, there is no center fence and the 35 delivery of the blanks from the stack is controlled by the corners thereof.

In the space between the two rails 72 works the chain 46 which may be of the roller chain type comprising vertically disposed links 76 connected 40 by pintles 78 on which are mounted rollers 80 which run on the fixed tracks 82 supporting the upper run of the chain and which rollers are engaged by the teeth of the driving sprocket 84 (Fig. 3). At suitable intervals the pintles secure 45 angles 86 to which are secured the feed dogs 48, which will next be described.

As best seen in Figs. 6 and 7, the feed dogs 48 comprise a depressed central portion and elevated offset end portions which overlie the rails 50 72 to push against the rear corners of the work piece as it gravitates onto the rails 72 in front of one of the dogs. To facilitate the rapid descent of successive pieces and positioning on the rails 72 to be picked up by a succeeding dog, the 55 rear corners of the dogs are truncated as seen at 88 in Fig. 6. Thereby while the dog as a whole is wide and sturdy, the engaging end portions are relatively short longitudinally of the machine. For the same reasons the rear edge of the 60 dog may be bevelled off as seen at 90. To provide for control of the work pieces substantially by their rear corners only and to facilitate disengagement of the dog as it turns downwardly about the leading sprocket the central portion of the 65 face of the dog may be bevelled off as illustrated at 92 in Figs. 6 and 9 whereby only the outer portions thereof which cooperate with the extremities of the rear edges of the blank have a wide and abrupt shoulder. To provide a support for the center portion of the blanks to prevent them from being unduly bowed down and to permit their edges to be presented to the rails 72 by the weight of the overlying stack, a central 70 stationary supporting rail or strip 94 (Fig. 5) 75 may be provided disposed substantially in the

plane of the rails 72 and overlying the depressed central portion of the feed dogs 48. Thus while the two end portions of the dogs are in fact integral and driven by a single chain and thus operate accurately in unison, the effect is of two dogs projecting through lateral slots in the support for cooperation solely with the outer portions of the blank as they rest upon the lateral supporting rails 72.

The chain 46 may be driven in any desired 10 manner, but I have here illustrated (see Fig. 5) the shafts of the sprockets 84 as connected by drive chain 95 and one as carrying the pulley 96 driven by belt 98 tensioned by the tightener pulley 100, this pulley being suitably weighted and 15 adapted when necessary to be thrown off by means of the handle 102 seen in Fig. 3 to stop the chain 46.

Referring now to Fig. 3, as the feed dogs deliver 20 the blanks from the hopper and start to travel downwardly about the leading sprocket, the edges of the blanks remain supported upon the side rails 72 or a continuation thereof, which support for the side edges of the blanks is substantially continuous throughout the machine, 25 except necessarily at the location of the bottom head 42 since it is desired to have the latter operate on the entire width of the blank. As the blanks are delivered from the hopper they pass through a suitable confining passageway which 30 prevents them from riding one over the other and maintains them properly in line to be forwarded in a series to the main feeding bed 54, which passageway comprises a bottom platen 104, of the side edges of which the rails 72 above referred 35 to form continuations, lateral guides 106 (see Fig. 1) and a top wall provided by the hold-down mechanism 52, hereinafter to be more fully described. The length of this passage in the embodiment shown is due in part to the fact that 40 structural convenience dictates that the hopper be organized at some distance from the feed bed 54.

The movement of the work pieces through this 45 passage may be effected by the transfer rolls 50 above referred to including the driven bottom roll projecting through a suitable opening 108 (see Fig. 5) formed in the platen 104, leaving, however, lateral portions thereof in alignment with the rails 72 which support the edges of the 50 work pieces and a top roll of divided or spool-shaped contour, so that in so far as its active surface goes it is in effect two rolls, cooperating therewith, this top roll being mounted on the swinging arm 110 and yieldably pressed toward 55 the bottom roll by the spring tension mechanism 112.

To insure the delivery of the work pieces in line along the platen to the transfer rolls 50 they may as they emerge from the front of the 60 hopper beneath the fences 74 pass beneath a hold-down 114 which may be mounted for vertical adjustment by means of the screws 116 on a bar 118 (see Fig. 4) carried on the front walls of the hopper, being herein shown as pivoted at 65 one side on a bolt 120 while the other end is provided with an open-sided notch adapted to take over a bolt 122 operated by a lever 124. This permits the right-hand end of the bar 108 to be quickly released in the case of a jam and the bar 118 swung upwardly about bolt 120 as a pivot to lift the hold-down 114. The hold-down may include a rearwardly and upwardly projecting finger 125 (see Fig. 3) extending closely adjacent the front wall of the hopper as defined by the 75

transverse flanges of the angle iron 70 and opposing the central supporting rail 94. If the center of a blank or work piece is upwardly bowed but its edges contact with the supporting rails 5 72, it may be fed out from under the other pieces in the stack because the fences defining this exit opening are solely opposite the edges of the piece. When, however, the forward end of the piece has advanced through this exit opening 10 and the work dog therefore has travelled beneath the overlying piece, the forward edge will be pushed beneath the central finger 125 which serves to flatten out the piece on the supporting rails and it is delivered substantially flat to the 15 transfer rolls 50. Lateral forwardly extending parts 127 (see Fig. 5) of the hold-down plate may oppose rails 72 and extend closely adjacent to the bite of rolls 50.

The top wall of the confining passage along 20 which the work pieces are advanced and constituting as a whole the hold-down mechanism identified by the numeral 52 may comprise primarily a longitudinal bar 126 which at the right extends between the two portions of the top roll 25 50 which is thus divided to permit this bar to extend past the center line of the roll and closely adjacent to the hold-down 114, as seen in Fig. 3, while at the left-hand end, as seen in Fig. 10, it overlaps the upper horizontal run of the feeding bed 54 extending substantially to the center line of the first of the hold-down rolls 58, which latter are of a construction to provide for this, as will hereinafter be described. This roll 58 is indicated at the left in Fig. 3. The bar 126 30 may be carried by the horizontal arm of an angular member 128 (see Fig. 5) sliding vertically on upright 130 and adapted for vertical adjustment thereon, its lowermost position being controlled by a limit screw 132 (see Fig. 2). A clamp 35 operated by the handle 134 serves to hold the bar stationary or releases the same to permit it to be quickly raised by means of a hoist handle 136 to permit jams to be cleared. The handle 136 passes through an opening in the vertical 40 leg of member 128, thus to obtain a bearing thereon, and is fixedly pivoted at its inner end on upright 130 and thus acts on the member 128 as a lever of the second class. In normal 45 operation the bar 126 may be considered stationary and serves as a limit for the upper wall of the passage. Auxiliary presser bars 137 (see Fig. 5) may be suspended from either side thereof by the springs 138 and serve to confine the work pieces against the platen 104, they 50 being normally raised so that their lower surfaces are substantially at the elevation of the lower surface of the bar 126.

Toward the left-hand portion of Figs. 3 and 5, the central portion of the platen 104 is cut away centrally to accommodate the circulating feed bed 54, the upper surface of which is disposed in alignment therewith. The lateral portions of the platen, however, continue as the rails 143 (see Fig. 12) which are in effect continuations of the rails 72 and continue the support of the work pieces by their lateral edges. The work pieces pass between the side guides 106 under the joint control of these rails 143 and the top bar 126 until under control of the feeding mechanism constituted by the feed bed 54 and its cooperating pressure rolls 58 which I will next describe.

The bed 54 may be of the general construction of that described fully in my Patent No. 1,704,677 75 and not necessary to describe in detail herein,

comprising essentially a chain of the roller type, the upper run of which is supported in a fixed horizontal plane by means of suitable supporting rails and which carries a series of transverse bars or lags 142 on which the work rests and by the motion of which the work is advanced. The lag bed and the cooperating pressure rolls 58, however, are herein of a peculiar construction. The bed works between the two rails 140 with its upper surface substantially in the same plane and the ends of the lags 142 are preferably rabbeted as at 144 (see Fig. 11) to fit around and beneath these supporting rails along which the bed advances the work pieces. The cooperating feed rolls 58 are, as best seen in Fig. 11, of spool-shaped form and cut away centrally, this permitting, as shown in Fig. 10, the continuation of the hold-down bar 126 into the cut-away portions of the active surfaces of the first of these rolls to overlie the horizontal feeding surface of 20 the bed. Also to maintain the pieces in position on the bed I may provide a central hold-down bar 146 received in the cut-away portions of the rolls and extending substantially from center line to center line as well as the lateral hold-down 25 bars 148 in alignment with the treads of the rolls and extending as closely as conveniently may be to the contact lines thereof. These bars are herein shown as suspended by an angle 150 carried by the roll housing. The drive of the bed and 30 the rolls may be substantially as disclosed in the patent above referred to and is unnecessary to describe here in detail.

The feeding mechanism shown in Figs. 10, 11 and 12 advances the work pieces through the 35 molding machine proper for the operation thereon of the cutter heads 40 and 42, each piece pushing forward those preceding it. The work pieces pass from the travelling bed 54 to a platen 152, the lateral edge portions of which are continuations of the rails 140 so that the edges of the work pieces have been continuously supported and guided in a fixed plane since their entry in the machine and supported in that plane as they pass from the bed 54 as it turns about the forward 45 sprocket in Fig. 10 to be advanced by the following piece on which the bed and its cooperating presser roll 58 maintains a grip.

The platen 152, as best seen in Fig. 14, extends beneath the top cutter head 40 of which the outline is shown in that figure and the work is supported thereon during the operation of the cutter head. The feed of the pieces by the feed bed 54 over the platen 152 is herein shown as controlled by a hold-down plate 154 supported 50 by an angular member 156, the vertical leg of which is vertically adjustable as by means of hand wheel 158 on a member 160, itself transversely adjustable on overhanging bracket 162. The work pieces pass from beneath this plate beneath the chip breaker. The chip breaker herein shown comprises a shoe 164 extending to the left in the figures into close proximity to the cutting circle of the top head 40 and which preferably may be made of synthetic resin such as that 55 known by the trade name "Bakelite", this shoe having rabbeted edges 166 (Fig. 17) sliding in ways in the metallic carrier member 168 pivoted at its right-hand end viewing Fig. 14 to the arms 170 of the chip breaker yoke which carries an 60 abutment lug 172 through which passes the stem of an eye bolt 174 pivoted on the carrier 168 and receiving (see Fig. 15) the spring 176 tending to rock the carrier 168 counterclockwise viewing Figs. 14 and 15 to provide suitable pressure upon 65 70 75

the chip breaker. The limit screw 178 extending through one of the arms of the yoke (Figs. 14 and 17) limits the upward swinging movement of the chip breaker. As is usual in devices of 5 this character, the chip breaker is mounted for adjustment, the chip breaker yoke being herein shown as vertically adjustable by means of the hand screw 180 swivelled therein and working in the supporting bracket 182 overhanging from one 10 side of the frame of the machine. A clamping device operated by the lever handle 184 is provided and a limit screw 186 for quickly returning the chip breaker to its initial adjusted position. To position shoe 164 in its supporting frame 168 15 and prevent its being carried too near to the cutter head, a member 188, best seen in Fig. 15, is secured thereto and preferably has the downwardly depending lug 190 entering a recess in the upper face of the shoe. The member 188 20 also has an upstanding flange 192 adapted to receive a set screw 194 cooperating with a suitable abutment surface on the part 168.

As the work pieces pass beneath the cutter head they are shaped substantially in the manner 25 shown in Fig. 33 and they continue beneath the cutter head over the platen 152 which extends, as best seen in Fig. 2, past the upper cutter head to the location of the lower cutter head. The work pieces are shaped as shown in Fig. 33, pass 30 over this platen beneath the hold-down 64 which extends over the lower cutter head and supports the work piece as it is acted on by the lower cutter head. This hold-down 64 takes the form of a suitable shoe, illustrated in Figs. 23 and 24, the 35 right-hand end of which viewing Figs. 24 and 2 extends closely adjacent the cutting circle of the upper cutter head 40. This shoe may be mounted as a whole in a frame 196, forming the horizontal arm of an L-shaped member, the other arm of 40 which 198 is here shown as sloping rearwardly of the machine and formed with the undercut guide-way 200 by which it may slide on the dovetailed upright 202 rising from the frame of the machine, the member being thus adapted for up and 45 down adjustment by means of the adjusting screw 204 which permits it to be quickly raised in a direction which carries it away from top cutter head 40 for clearing out jams. The shoe 64 is itself secured in its support, as best seen in Fig. 50 24, by means of the screws 206 tapping into the back thereof and the set screws 208 adapted to bear against the sides thereof for adjusting it laterally.

In accordance with my invention, as best seen 55 in Fig. 25, the bottom of the shoe 64 is provided with a series of grooves 210 so that it presents surfaces cooperating with the shaped surface of the work piece as shown in Fig. 33. Herein these 60 grooves are substantially semi-circular and in the case of work which is cut in cylindrical form so that the surfaces of Fig. 33 are semi-circular, they substantially fit about the same. The semi-circular groove, however, will efficiently cooperate with surfaces of somewhat different shape 65 providing for each partially cut rod bearing lines at either side thereof. By means of this hold-down plate the partially severed blank is advanced toward the bottom head with its parts accurately positioned for accurate operation of 70 the knives at the bottom head thereof to form the desired rods and possible breaking or splintering of the partially formed blank as it is pushed along is prevented. The grooves, as seen in Fig. 26, continue throughout the length of the plate 64 75 but are relieved at the location of the bottom

head 42; that is, the projecting ribs which define them are there partially cut away (see Fig. 26). It will be understood that as the work passes the lower head the blank is divided longitudinally into separate rods, as indicated in 5 Fig. 34. In other words, at the left of the cutter head viewing Fig. 26 we no longer have a continuous width of wood, but on the contrary a series of spaced rods. These, however, are positioned in the grooves and there is no tendency 10 for them to become displaced transversely of the machine.

The left-hand end of the hold-down plate overlaps, as seen in Fig. 28, the feeding-out platen 212 which is mounted in a manner hereinafter to be 15 more fully described on a support 214 which may be pivoted on a center not shown, being beyond the range of the drawings in Fig. 2 and 28, to permit it to be swung away from the lower head in a manner not new in connection with feeding- 20 out tables of molding machines and may be normally held in the position shown in Fig. 2 by means of latches 218. For present purposes this framework 214 may be considered as stationary. The platen 212 may be formed to slide thereon 25 on diagonal ways 230 so as to move at the same time inwardly toward the cutter head and upwardly to a final adjusted position determined by a limit screw 232 (Fig. 30) and toward which it is pressed by the lever 234 under the influence of 30 spring 236 carried by the rod 238. A cam 240 adapted to be moved by a lever handle 242 provides for quickly moving the table outwardly and downwardly against the force of the spring, thus giving access to the cutter head and also moving 35 the end of the platen away from the hold-down 64. Moving with the table is a frame 244 on which are pivoted arms 246 in which is journalled the rubber covered feed-out roll 248 opposing the platen 212. The roll 248 is circumferentially 40 grooved in alignment with the grooves of 64 to guide the completed rods from the cutter head and over the feed-out table. The movement of this roll against the table may be controlled by a limit screw 250 and its tension by means of 45 weights 254 (see Fig. 27) carried by a cross-bar 252 connecting the journals of the arms 246.

The arrangement of the feed-out platen 212 as above described provides for exerting a retarding pressure on the rods as they leave the machine 50 by the frictional grip thereon of the opposed edges of the hold-down plate 64 and the feeding-out platen 212. This resists the feeding movement of the rods communicated by the following work pieces under control ultimately of the feed bed 54. 55 This holds successive pieces together and in the grooves of the hold-down plate 64 as the pieces pass over the gap between feeding-out platen 212 and the end of platen 152 at opposite sides of the bottom head. Thus when the line between successive pieces passes over this gap the opposed ends are held pressed together so that the effect of this break in the continuity in tending to permit the parts to become displaced is minimized. To facilitate this action I prefer to provide for 60 pinching the stock along a transverse line at the intake side of the lower head as well as on the out-going side as already described, and for this purpose the lower end portion 256 of the platen 152 may, as best seen in Figs. 28 and 31, be formed 70 separately and pivoted on a transverse pivot 258 and normally pressed upwardly by means of a stud 260 supported by a spring 262, the tension of which may be adjusted by means of the screw-operated follower 264. A limit screw 266 con- 75

trols the downward movement of the part 256. By this arrangement the rear edge of platen 152 is slightly canted upwardly to press in a limited transverse zone against the overhanging plate 64 to pinch the stock just as it passes to the bottom cutter head.

In various places in the drawings portions of the mechanism for driving the various moving parts are illustrated but in other instances have been omitted. For example I have not attempted to show the drive for the two cutter heads which might be effected by integrally connected electric motors, neither have I thought it necessary to describe in detail all the portions of the drive which are illustrated as to do so would merely lengthen this description without being correspondingly useful to those skilled in the art. It will be apparent from the description what parts move and the method of moving them may be in accordance with analogous prior practices in the art.

As regards the speed of movement of the moving parts, the linear speed of the feed bed 54 may be considered as the rate of feed of the machine as a whole. This is designed to forward the pieces to the heads in an end butted row. Since the dog chain 46 delivers the pieces with gaps therebetween corresponding substantially to the width of the dogs, this chain may be driven at a substantially greater linear speed in order to make up these gaps, and the intention in the form of the machine shown is that the pieces of stock shall be butted end to end as they are delivered to the rolls 50. The yielding nature of the drive 35 of the chain 46 by means of the belt 98 and the tightener pulley 100 permits slippage where necessary. The speed of the transfer rolls 50 is desirably slightly greater than the speed of the feed belt 54 in order to insure that the pieces travel 40 through the transfer passage in an unbroken succession and are delivered butted to the feed belt. This slight excess of speed also serves to close up any slight gap which might remain between successive pieces. The yielding mounting of the upper roll of the pair 50 permits such yielding of the feed as may be necessary due to the slight differential in speed required.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. In a machine of the class described the mechanism for separating successive pieces of stock from a supply and advancing them for delivery to the molding mechanism proper comprising a hopper, rails beneath and constituting a bottom for the hopper at either side thereof, fences above said rails, the front of the hopper at the bottom being separated from the fences by spaces, a chain having a run between the rails, and feed dogs carried by the chain having ends overlying the rails to move through said spaces.

2. In a machine of the class described the mechanism for separating successive pieces of stock from a supply and advancing them for delivery to the molding mechanism proper comprising a hopper, rails beneath the hopper at either side thereof, fences above said rails, a chain having a run between the rails, a central rail above the chain, and feed dogs carried by the chain hav-

ing central portions underlying said central rail and upwardly offset ends overlying the lateral rails.

3. In a machine of the class described the mechanism for separating successive pieces of stock from a supply and advancing them for delivery to the molding mechanism proper comprising a hopper, rails beneath the hopper at either side thereof, fences above said rails, the front of the hopper at the bottom between the fences being open, a chain having a run between the rails, a central rail above the chain and feed dogs carried by the chain having central portions underlying said central rail and upwardly offset ends overlying the lateral rails and an upwardly and rearwardly sloping hold-down plate directly above said central rail closely adjacent the exit opening beneath the fences.

4. In a machine of the class described, in combination with a molding mechanism proper comprising cutters and means for advancing the work therethrough, means for separating pieces of stock from a supply and presenting them to the machine and transfer mechanism between them comprising a passageway including a platen, side fences and a top hold-down bar, and feed rolls for receiving a presented piece and forwarding it along said passageway, said bar extending past the feed rolls to maintain control of the pieces as it passes the rolls.

5. In a machine of the class described, in combination with a molding mechanism proper comprising cutters and means for advancing the work therethrough, means for separating pieces of stock from a supply and presenting them to the machine and transfer mechanism between them comprising a passageway including a platen, side fences and a top hold-down bar and auxiliary bars spring-supported therefrom, and feed rolls for receiving a presented piece and forwarding it along said passageway, said bar extending past the feed rolls to maintain control of the pieces as it passes the rolls.

6. In a machine of the class described, in combination with a molding mechanism proper comprising cutters and means for advancing the work therethrough, means for separating pieces of stock from a supply and presenting them to the machine and transfer mechanism between them comprising a passageway including a platen, side fences and a top hold-down bar, said bar having quick acting hoist means, and feed rolls for receiving a presented piece and forwarding it along said passageway, said bar extending past the feed rolls to maintain control of the pieces as it passes the rolls.

7. In a machine of the class described, in combination with a molding mechanism proper comprising cutters and a feeding couple for advancing the work therethrough, means for separating pieces of work from a supply and presenting them to the machine and transfer mechanism between them including a platen, side fences and a top hold-down bar, and feed rolls for receiving a presented piece and forwarding it along said passageway, said bar overlapping said feed rolls and said couple to maintain control of the piece as it passes the rolls and until it is held by the couple.

8. In a machine of the class described, in combination with a platen and a cutter head opposing the same over which platen and beneath which cutter head a series of work pieces are advanced in end-butted relation for operation of the head thereon, rails aligned with the platen at the intake side thereof for marginally supporting the

- work pieces and feeding means comprising a circulating bed having its upper run disposed between said rails and substantially coplanar therewith, and pressure means cooperating with the bed to hold work pieces against the bed for advance thereby over said platen and beneath the cutter head.
9. In a machine of the class described, in combination with a platen and a cutter head opposing the same over which platen and beneath which cutter head a series of work pieces are advanced in end-butted relation for operation of the head thereon, rails aligned with the platen at the intake side thereof for marginally supporting the work pieces and feeding means comprising a circulating bed having edges rabbeted to fit beneath said rails and expose its central portion between the same substantially in the plane of the upper faces thereof, and pressure rolls cooperating with the bed to hold work pieces against the bed for advance thereby over said platen and beneath the cutter head.
10. In a machine of the class described, in combination with a platen and a cutter head opposing the same over which platen and beneath which cutter head a series of work pieces are advanced in end-butted relation for operation of the head thereon, rails aligned with the platen at the intake side thereof for marginally supporting the work pieces and feeding means comprising a circulating bed having its upper run disposed between said rails and substantially coplanar therewith, longitudinal bars supported above the bed between the rails to confine the work pieces thereon, and pressure rolls extending past said bars into cooperation with the bed to hold work pieces against the bed for advance thereby over said platen and beneath the cutter head.
11. In a machine of the class described, in combination with a platen and a cutter head opposing the same over which platen and beneath which cutter head a series of work pieces are advanced in end-butted relation for operation of the head thereon, rails aligned with the platen at the intake side thereof for marginally supporting the work pieces and feeding means comprising a circulating bed having its upper run disposed between said rails and substantially coplanar therewith, a passageway through which the pieces are advanced to said bed comprising a platen, side walls and a top bar, which bar is extended to overhang the bed, and pressure rolls cooperating with the bed to hold work pieces against the bed for advance thereby over said platen and beneath the cutter head.
12. In a machine of the class described, in combination with a platen and a cutter head opposing the same over which platen and beneath which cutter head a series of work pieces are advanced in end-butted relation for operation of the head thereon, rails aligned with the platen at the intake side thereof for marginally supporting the work pieces and feeding means comprising a circulating bed having its upper run disposed between said rails and substantially coplanar therewith, a platen over which the pieces are advanced to the bed, lateral confining walls cooperating with the platen, longitudinally disposed confining means supported above the platen and the bed to maintain continuous control of the pieces during their passage thereover, and pressure rolls projecting inwardly past said confining means into cooperation with the bed to hold work pieces against the bed for advance thereby over said platen and beneath the cutter head.
13. A machine of the class described comprising a cutter head to groove a face of the work piece and a succeeding head operating on the other face to divide it into rods, a platen between the heads, a hold-down plate opposing the platen extending over the latter head, and means at the delivery side of the head cooperating with the end of said plate to pinch the rods thereagainst at the delivery side of the head comprising a feeding-out table mounted on diagonal ways extending downwardly and in the direction of feed movement and normally spring-pressed therealong upwardly and against the direction of feed movement toward the work and said head.
14. A machine of the class described comprising successive upper and lower cutter heads for operating on the faces of the stock, substantially continuous longitudinal supporting rails to underlie the lateral edges of the stock and extending substantially to the lower head, means for supporting a stack of work pieces between said rails including fences disposed over said rails and presented to the leading edge of the work pieces adjacent their outer margins solely, defining an exit opening controlling the delivery of the pieces therethrough by the edge portions thereof means operating above said rails and between the rails and said fences, respectively, for delivering successively lowermost pieces of the pile through the opening, and subsequent feeding means for engaging the central portion of the pieces as supported by the rails for forwarding the same from said delivery means in an end-butted row to the cutter heads.
15. A machine of the class described comprising successive upper and lower cutter heads for operating on the faces of the stock, substantially continuous longitudinal supporting rails to underlie the lateral edges of the stock and extending substantially to the lower head, means for supporting a stack of work pieces between said rails including fences disposed over said rails and presented to the leading edge of the work pieces adjacent their outer margins solely, defining an exit opening controlling the delivery of the pieces therethrough by the edge portions thereof means operating above said rails and between the rails and said fences, respectively, for delivering successively lowermost pieces of the pile through the opening, and subsequent feeding means for engaging the central portion of the pieces as supported by the rails for forwarding the same from said delivery means in an end-butted row to the cutter heads.
16. A machine of the class described comprising successive upper and lower cutter heads for operating on the faces of the stock, substantially continuous longitudinal supporting rails to underlie the lateral edges of the stock and extending substantially to the lower head, means for supporting a stack of work pieces between said rails including fences disposed over said rails and presented to the leading edge of the work pieces adjacent their outer margins solely, defining an exit opening controlling the delivery of the pieces therethrough by the edge portions thereof means operating above said rails and between the rails and said fences, respectively, for delivering successively lowermost pieces of the pile through the opening, means presenting to the central portions of the work pieces as they pass from the hopper a face sloping downwardly in the direction of feed and receiving the pieces as they are delivered along said rails for flattening the same transversely, and subsequent feeding means for engaging the central portion of the pieces as supported by the rails for forwarding the same from said delivery means in an end-butted row to the cutter heads.

LAURENCE E. BLOOD.
